UNITED STATES PATENT OFFICE.

FRED A. REARDON, OF BRIDGEPORT, CONNECTICUT, ASSIGNOR TO HAMEL SHOE MACHINERY COMPANY, OF BRIDGEPORT, CONNECTICUT, A CORPORATION OF MASSACHUSETTS.

COUNTERTURNING MACHINE.

Application filed October 6, 1920. Serial No. 415,087.

To all whom it may concern:

Be it known that FRED A. REARDON, a citizen of the United States, residing at Bridgeport, in the county of Fairfield and State of

- 5 Connecticut, has invented certain new and useful Improvements in Counterturning Machines, of which the following is a specification, reference being had therein to the accompanying drawings.
- 10 This invention relates to machines of the cup and plunger type particularly designed for turning the counter portions of turn shoes. As usually constructed the plunger is carried by a swinging arm, and in order
- 15 to cause the rear edge of the plunger to clear the top edge of the cup and yet cause the counter to conform to the desired contour, it has been customary to cut away the lower rear face of the cup to allow room
- 20 for the upper to bend while the cup is being pushed forward against the plunger during the latter part of its turning movement.

This invention provides simple means by 25 which the plunger is given a movement to properly shape the counter without the necessity of moving the cup, and which allows the use of a cup having a solid undercut rear wall. This form of cup cooperat-

30 ing with the plunger produces a wiping and pressing action on the counter which acts to smooth the latter preventing much of the wrinkling usually produced by the turning operation. Preferably the movement of the

35 plunger against the rear face of the cup is made yielding.

While a solid cup may be employed, this invention further contemplates the use, if desired, of a modified form of cup which 40 is composed of two parts, one of these parts, comprising the major portion of the cup side faces, being rigidly fixed, while the other part comprising the back face of the cup and the remaining portions of the side faces, is so mounted as to yield rearwardly under pressure of the shoe and plunger thereagainst. With this form of cup, the yielding movement of the plunger may be dispensed with, if desired, or it may be used

45 in addition thereto.

For a more complete understanding of this invention, with other objects and advantageous details of construction and combination of parts, reference may be had to 50 the accompanying drawings in which,

Fig. 1, represents a side elevation partly broken away of the upper portion of a counter-turning machine constructed according to this invention.

Fig. 2, represents a section taken on line 60 2-2 of Fig. 1.

Fig. 3, is a fragmentary detail of a link connection.

Fig. 4, is a detail cross section of the latch means for retaining the cup turret in position. 65

Fig. 5, is a side elevation of a modified form of cup, a portion of the supporting turret being shown in section.

Fig. 6, is a rear elevation of the lower 70 portion of the same parts.

Fig. 7, is a partial cross section on line 7-7 of Fig. 5, while,

Fig. 8, is a partial cross section on line 75 8-8 of Fig. 5.

Referring to Figs. 1 to 4 inc., A represents the upper portion of a machine standard carrying a head or frame B for supporting the turning implements. At its forward end, the head B has a forwardly and upwardly extending bracket 1 having an inclined end 2 and recessed at 3 to receive the pivot 4 of a cup carrying turret 5. As shown, this turret has a plurality of dovetail slotted cup carrying arms 6 to which 80 cups 7 of various sizes may be made fast, each cup having a dove-tail mating the slot in the arm 6, and being fixed in position by any suitable means such as a screw clamp, as shown at 7a. The cup 7 has 85 up-standing side faces 8 and 9, and an undercut rear face 10, and is open on its forward side in the usual manner. The turret 5 is retained in position on the bracket 1 by means of a set screw 11 engaging a circumferential groove 12 in the pivot 4. It is held in position with any desired cup in operative position, by means of a latch bolt 13 seated in a recess in the bracket 1 and pressed outwardly by means of a spring 14, suitably spaced perforations 15 being provided in the turret 5 for engagement with the bolt 13 when a form is properly positioned. A retracting finger 16 projects 90 outwardly from the latch bolt and provides 95 means for disengaging the same from the turret.

The head B has an upstanding bracket portion C of substantially U form in cross section, the open portion of the U facing for- 100 110

wardly. At its upper end member C has pivoted thereto, spaced arms 20 and 21 of a link 22 which at its outer end has a slot 23 therein for the sliding reception of a pivot pin 24. Beyond the slot 23 link 22 has a perforated boss 25 for the slideable reception of a pin 26 which is threaded at its inner end and screwed into a mating threaded opening in the pivot 24. The outer end of pin 26 is 10 threaded at 27 for the reception of a thumb nut 28, and a spring 29 surrounding the rod 26 bears at one end against the boss 25 and at the other against the nut 28. This spring 29 acts to hold the pivot 24 yieldingly at its 15 outward limit of motion within the slot 23, the force of its action depending on the adjustment of the nut 28.

The pivot 24 is fixed between the upper end of flanges 30 and 31 of a bar 32 of U 20 shape cross section. The lower end of bar 32 terminates in a reduced solid portion 33 having a socket 34 for the reception of a shank 35 of a turning implement comprising a plunger 36 which may be made fast in position 25 by a set screw 37. Below the link 22, and arranged out of parallelism therewith, is a link mechanism comprising a pair of arms 40 and 41 pivoted at their inner ends at 42 to the side flanges of the brackets C 30 and at their outer ends pivoted between the flanges 30 and 31 of bar 32 by the pin 43. Also pivoted on the pin 43 and positioned between the members 40 and 41 is an upwardly extending link 44, to the upper end 35 of which is pivoted at 45 the forward end of a lever arm 46, fulcrumed at 47 between rearwardly extending ears 48 and 48^a carried by the member C, the rear wall of this member terminating therebelow to allow play of the 40 lever 46. Between the pivots 45 and 47, a rod 49 is pivoted at 49' to the lever 46, this rod projecting downwardly through the base of the head B and into the standard A where it may be attached to any suitable means 45 for depressing it, such as a treadle, not shown. A coil spring 50 is made fast at its upper end adjacent the top of the standard A and at its lower end to a collar 51 adjustably fixed to the rod 48.

50 The operation of this mechanism is as follows:

In normal position of the parts spring 50 55 acting against the rod 49, holds the outer end of lever 46 upwardly and acting through the link 44 and the pivot 43 retains the plunger 36 out of the cup and raised sufficiently thereabove so that the operator may place the counter of a shoe to be turned over the cup 7 with the rear inner face of the 60 counter against the outer rear face of the cup. On depressing the rod 49 by means of the treadle, the plunger 36 is now brought down against the heel portion of the shoe at the point of attachment of the upper to 65 the sole. On further depressing the treadle,

plunger 36 is forced downwardly within the cup, turning the counter over the side and rear edges thereof, the sole passing down through the open front end. As the plunger advances within the cup the angular relation of the links 22 and 40 and 41 causes the plunger to move rearwardly toward the rear wall or closed end of the cup, thus substantially following its undercut contour and pressing the counter firmly thereagainst and wiping the sides of the counter against the cup side faces. It should be noted that the link comprising the arms 40 and 41 is out of parallelism with the link 22, the outer ends of these links being further apart than their inner ends. This arrangement causes the pivot 43 to move inwardly toward the bracket C while the pivot 24 is still substantially at its furthest position therefrom by which action, the required motion of the plunger rearwardly is produced. It should also be noted that the spring 29 allows the upper end of the bar 32 to yield inwardly and thus imparts a yielding pressure between the plunger and the rear face of the cup.

On the operator releasing the treadle, spring 50 returns the plunger to its upper position and allows the shoe with its counter turned to be removed from the cup. The latter part of the upward movement of the plunger is substantially vertical since the links 22 and 40, 41 are both approximately at their horizontal position. By this means it is seen that the plunger is moved in a non-circular curved path of variable radius, the radius decreasing as the plunger moves into the cup, this action of the parts molding the counter to its proper form without necessitating movement of the cup.

In Figs. 5 to 8, is shown a modified form 105 of the cup which may be used if desired. With this modification, the arm 6' of the cup supporting turret, is provided with a dove-tail slot 60 longitudinally thereof, and at its outer end is an upstanding lug 61. Slidable within the groove 60 is a mating 110 dove-tail 62 fixed to or integral with the rear portion 63 of the turning cup 7'. The dove-tail 62 is cut through vertically for a portion of its length at its forward end for the reception of a depending rib 64 fixed to or integral with a forward section of the cup, this section comprising upstanding portions 65 and 66 at either side which form the 115 major portions of the lateral sides of the cup, the latter being open on its forward side as in the form heretofore described.

The rear cup portion 63 has forwardly extending portions one of which is shown in Fig. 5 at 67 normally projecting over the portions 65 and 66 and completing the top side portions of the cup. The forward cup portion is fixed in position on the arms 6' by means of a bolt or cap screw 68 passing 125 through a perforation in the arm 6' and 130

having threaded engagement with a perforation in the rib 64. The rear portion of the dove-tail 62 is recessed at 69 and a spring 70 bearing at its forward end against the base of this recess and at its rear end against the lug 61 normally urges the rear cup portion forwardly into close contact with the forward cup portion. A pin 71 threaded in the lug 61 enters the coils of the spring 70 and serves as a guide therefor. When this cup is being used, and the plunger descends therein to turn the shoe, the rear portion of the cup is allowed to yield relative to the sides by the action of the the spring 70 the stationary side members 65 and 66, engaging the counter portions of the shoe on either side, acting as wipers to smooth the upper forwardly from the heel end during the rearward motion of the plunger and shoe against the rear cup portion. When the plunger is lifted from the cup, the rear portion thereof moves forwardly through the action of the spring 70 into its former closed position.

Having thus described certain embodiments of this invention, though it is evident that many changes and modifications might be made therein without departing from its spirit or scope, what is claimed is:

1. In a turning machine, a cup having side walls and a rear wall of non-circular curvature from top to bottom, and a plunger movable into said cup and backwardly toward the rear wall thereof.

2. In a counter turning machine, a cup having a rear wall backwardly offset from its upper edge toward the bottom, a plunger movable into said cup to turn the counter of a shoe, and means for supporting and guiding said plunger constructed and arranged to move said plunger toward the rear wall of said cup at a gradually increasing rate as said plunger passes within said cup.

3. In a turning machine, a movable turning element, a pair of controlling links pivotally sustaining said turning element, and means for actuating said links in unison in substantially the same direction to move said element in a curved path of variable radius.

4. In a turning machine, a movable turning element, and a pair of non-parallel pivoted links each movable about a fixed fulcrum at one end and together controlling the path of movement of said element.

5. In a turning machine, a movable turn-

ing element, a pair of non-parallel pivoted links controlling the path of movement of said element, and a yielding element interposed between one of said links and said turning element.

6. In a counter-turning machine, a supporting frame, a cup carried by said frame, a plunger, a pair of links of different lengths each pivoted at one end to said frame and at the other end to said plunger and constraining said plunger to move in a plane into and out of said cup, and means for so moving said plunger.

7. In a counter-turning machine, a supporting frame, a cup carried by said frame, a plunger, and a pair of non-parallel links each pivoted at one end to said frame and at the other end to said plunger and constraining said plunger to move into and out of said cup and toward and from one side of said cup in a non-circular curved path.

8. In a counter-turning machine, a supporting frame, a cup carried by said frame, a plunger, a pair of non-parallel links each pivoted at one end to said frame and at the other end to said plunger and constraining said plunger to move into and out of said cup and toward and from one side of said cup in a non-circular curved path, means for cushioning said motion toward the side of said cup, and means for moving said plunger.

9. A cup for a shoe-turning machine having side walls and a rear wall continuous therewith but adapted to yield relatively thereto.

10. A cup for a shoe turning machine having rigid side faces and a yielding rear face forming a continuation thereof.

11. A cup for a shoe turning machine comprising side and rear faces having a rigid portion comprising the major portion of said side faces, and a portion yieldable from said rigid portion and comprising said rear face and the remaining portions of said side faces.

12. A cup for a shoe turning machine having an under-cut rear face curved from top to bottom to conform with a finished shoe-counter, and means for yieldingly maintaining said rear face in operative position during turning operations.

In testimony whereof, I have signed my name to this specification.

FRED A. REARDON.
